UNITED STATES PATENT OFFICE.

ALLEN J. TANNER, OF FRANKLINVILLE, NEW YORK, ASSIGNOR OF ONE-HALF
TO ALBRO O. HOLMES, OF SAME PLACE.

CAN-FILLING MACHINE.

SPECIFICATION forming part of Letters Patent No. 518,973, dated May 1, 1894.

Application filed January 29, 1894. Serial No. 498,350. (No model.)

To all whom it may concern:

Be it known that I, ALLEN J. TANNER, of Franklinville, in the county of Cattaraugus and State of New York, have invented certain new and useful Improvements in Pea-Fillers; and I do hereby declare that the following description of my said invention, taken in connection with the accompanying sheets of drawings, forms a full, clear, and exact specification, which will enable others skilled in the art to which it appertains to make and use the same.

This invention has general reference to machines for mechanically filling peas into cans; and it consists, essentially, in the novel and peculiar combination of parts and details of construction, as hereinafter first fully set forth and described, and then pointed out in the claims.

In the drawings already referred to, which serve to illustrate my said invention more fully, Figure 1 is a side elevation of my improved pea filler, portions of its frame being broken away to disclose underlying parts. Fig. 2 is an end view of the machine from the supply-end thereof. Fig. 3 is a transverse sectional elevation in line xx of Fig. 1. Fig. 4 is a plan of the lower portion of the machine below the line yy of Fig. 3. Fig. 5 is a longitudinal sectional elevation of a portion of the machine drawn on a larger scale to more clearly illustrate the details of construction.

Like parts are designated by corresponding letters of reference in all the figures.

The object of this invention is the production of an efficient machine for mechanically filling cans with peas, the machine being especially designed for use in canning establishments where during the proper season a large number of cans are daily filled with this vegetable product, its daily capacity being over twenty thousand of the so-called two pound, or No. 2 cans. To attain this result I construct this machine substantially of a receiver for the peas; a series of filling and gaging cylinders or tubes, secured to a plate; a striking or jarring mechanism by means of which this plate and its attached tubes are rapped or vibrated so as to jar the same and thereby to cause the discharge of the peas from the said tubes; mechanism for feeding

the cans and placing them into proper position, and a brining mechanism to supply the cans with the proper amount of brine, the whole being arranged in a suitable frame so as to be self-contained, as will hereinafter more fully appear.

In the drawings, Figure 1, A is a frame constructed of hard wood and composed of four uprights or posts A' , A^2 , A^3 and A^4 , connected together near their lower ends by two longitudinal rails $B B'$, and two cross rails $E E'$, and at their upper ends by a receiver G , consisting of a rectangular box composed of the longitudinal sides G'' , transverse ends $g g'$ and bottom G' , said uprights being secured to said receiver in any suitable and secure manner.

Above the lower cross rails $E E'$ are provided a cross-board C , connecting the uprights A^2 and A^3 , and a cross-rail D , connecting the uprights A' and A^4 . Upon this cross-board and cross rail is located a track-board F , projecting from both ends of the frame A and having on one end a supporting leg M , and at the opposite end, (being the rear end of the machine,) two legs $a a'$, connected with the lower longitudinal rails $B B'$ in a suitable manner. This track-board F terminates in a table F' , as clearly illustrated in Figs. 1 and 4.

In the bottom G' of the receiver G there is a longitudinal recess or depression g'' , Fig. 5, of proper width and depth and nearly the entire length of the said receiver G , into which recess is placed a tube-plate H . This tube-plate is preferably made from sheet metal, such as brass, copper or similar metal possessing the necessary degree of ductility and it has two rows of circular apertures or holes H' , as shown in detail in Fig. 5, within which are secured a like number of cylinders or tubes J , also preferably made of brass or copper. In the present instance I have shown in Fig. 1 thirteen of these tubes in a row, making twenty-six in the two rows, but in practice I may vary the number by an increase to twenty-eight (or less) of the tubes without materially changing the character of my said invention. This tube plate H has in its center-line a number of studs h'' , the object of

which will hereinafter be explained. From its lower surface are pending eight, (more or less) screw rods I' , to connect it with a tube-steadying plate I having a number of circular 5 apertures m' , corresponding with those in the tube-plate H and fitting the said tubes a close fit. These screw rods I' are properly screw-threaded at their lower ends and provided with lock-nuts i'' , above and below the tube- 10 steadyng plate I to enable me to properly adjust and hold the said tube-steadying plate in position.

Above the cross-board C and cross rail D there are two other cross rails $C' C''$, connecting the uprights A' and A^4 as well as the uprights A^2 and A^3 respectively. These cross-rails $C' C''$ have in their center four adjusting screws k , shown in Figs. 1, 3 and 5, which screws are fastened with their lower ends in 15 a gate-plate K , and are freely passed through the said rails, adjusting nuts $k' k''$ being placed upon said adjusting screws k above and below the rails $C' C''$ to enable me to raise and lower the gate-plate K . This adjustment enables me to increase and decrease 20 the capacity of the tubes J which do not project through the gate-plate K but stop short of the lower surface thereof so that by lowering the gate-plate K the capacity of the tubes J is increased, while raising the said gate-plate 25 decreases the capacity in a manner readily understood, there being a series of circular apertures m , in said gate-plate K for the reception of the lower ends of the said tubes J , for this purpose. Below this gate-plate K , and running in grooves therein is located a 30 slide or gate K' , having a series of circular apertures b , Fig. 5, registering with the apertures m in the gate-plate K , said slide K' being operated by a lever L , Figs. 1 and 3, having its fulcrum in a bracket l' , and engaging with its lower end double eyes l , on the end of said gate K' . By pushing this lever L in one direction it will cause the slide K' to move in the opposite direction and to bring 35 its apertures b into register with those in the gate-plate K and thereby to open the lower ends of the tubes J , while manipulating the lever in the opposite direction causes the 40 slide to close said tubes, the apertures in said slide K' occupying a position between those in the gate-plate which are spaced far enough apart for this purpose. On this gate or slide K' there are provided end-stops $K'' K'''$, to 45 properly limit the movement of the gate, but other suitable stops may be provided on the lever L , if desired, for the purpose mentioned.

To the end-boards $g' g'$ of the receiver G are fastened brackets N, O , respectively, both of which are provided with bearings n, o , for the reception of a shaft P , receiving motion through a bevel wheel p , engaging a bevel-spur wheel p' , secured to a short shaft P' , having its bearing n' in an arm N' , projecting from the bracket N . On the outer end

of this shaft P' is fitted a pulley Q , provided with a clutch q , so that by moving said clutch q by the lever Q' (fulcrumed at q' on the end-board g'), into contact with said pulley Q , 70 said shaft P' is revolved and through it and the bevel gearing, also the shaft P . Upon this latter shaft are secured two eccentrics $R R'$, which, in turn, are connected with a cross-head S , by their straps and connecting rods $r r'$, the lower ends of which engage double eyes $s s'$, on said cross-head S . This cross-head S is so arranged that in its downward movement imparted to it by the eccentrics and accessories it will strike upon the studs h'' in the tube-plate H and thereby to jar or vibrate the same, spiral springs h' , Figs. 3 and 5, located under said tube-plate H giving to 80 said tube-plate the necessary elasticity, while screw-bolts h , in said tube plate and passing through the bottom G' of the receiver G , prevent the upward movement of said tube-plate beyond a fixed limit. This cross-head S operates in suitable guides $S' S''$, Fig. 5, provided on the inner side of the end-boards $g g'$. 90

To the cross-board C are fastened two bearings $c c'$, Fig. 2, within which revolve a shaft T , upon which is placed a pulley T' , connecting with the pulley Q on the shaft P' by a belt t , and a further pulley T'' loosely revolving upon said shaft T but connected and disconnected therewith by a clutch t' , operated by a lever t'' , Fig. 1, said pulley T'' being the main driving pulley and connected with a main shaft or other source of power, by 100 belting in any suitable manner. These two pulleys $T' T''$ are connected together in any suitable manner, or they may be a single pulley of the required width, if so desired.

To the outer end of the shaft T is fastened 105 a crank d , connected, with a connecting rod d' , with a plunger d'' , of the pump D'' . This pump has a suction pipe e , leading to a suitable supply tank not shown, which contains the brine, and a discharge pipe e' terminating in a nozzle e'' located at the rear end of the machine above the table F' , as shown in Fig. 1. This pump-mechanism supplies the cans with brine after they have received their proper charge of peas, as will be hereinafter 115 more fully explained.

To the inner end of the shaft T is fastened another crank U , which connects with a sliding pusher V , by the connecting rod U' . This pusher V moves in guides $v v'$, fastened upon the track-board F and passes through a fixed hopper V' , into which the cans J' to be filled are passed by a suitable spouting pipe V'' . These cans, after being pushed out of the hopper by the pusher, move along a single fixed 125 track W to a switch-track W' , hinged to the fixed track at w , and operated by a lever mechanism hereinafter to be described.

Upon the track-board F are secured track-rails f, f', f'' , placed sufficiently far apart to 130 admit two rows of cans between them, the central track f' separating the two rows of

cans and preventing them from being misplaced. From the fixed track W these cans are led into one or the other of the two ways *j j'* by the switch-track W' so that the holes 5 in the cans are directly underneath the apertures *b* in the slide K', while on the rear end of the machine upon the track-board F there is another switch track X', and a fixed discharging track X. These switch tracks W' 10 and X' are connected, by means of connecting rods *x x'*, to levers Y Y', having their fulcra at *y y'* respectively, and being jointed at their meeting ends by a bolt *y''*, in such a manner that by operating the lever Y' both 15 switch-tracks W' X' will be moved simultaneously.

The operation of this machine is as follows:—Motion is communicated by the pulley T'' T' to the shaft T and the pump and pusher 20 as well as to the shaft P and the jarring mechanism. The cans to be filled are passed through the spouting pipe V'' into the hopper V' and by the pusher V passed along the fixed track W and switch-track W' into the 25 way *j'* until a sufficient number of cans occupy this way to correspond with the number of tubes J above the same. Now the lever Y' is pushed over to move the switch-tracks W' Y' to the opposite way *j* and the 30 cans moved along this way until it also is supplied with the requisite number of cans. During this portion of the procedure the rapping mechanism is at rest, the clutch *q* having been disengaged from the pulley Q. Now 35 the pusher is stopped by disengaging the clutch *t'* from the pulley T'', when two operators standing one on each side of the machine pass the peas dumped into the receiver G into the tubes J until they are filled, when 40 the rapping mechanism is started and the slide K' pulled, to cause its series of apertures *b* to correspond with the apertures *m* in the gate-plate and the peas to discharge from the tubes into the cans beneath, the discharge being as- 45 sisted by the jarring of the tube-plate by the jarring mechanism. As soon as the peas are discharged from the tubes, the slide K' is moved to close the lower end of the tubes and the pusher started. This will cause the 50 cans in the way *j'* to move over the switch-track X' upon the fixed track X where as soon as a can reaches the spot directly underneath the nozzle e'' it will receive a charge of brine from the pump D'' through the discharge 55 pipe e', it being understood that the movement of the cans is an intermittent one and that the pump and the pusher operate in unison and that the discharge of the pump takes place during the receding portion of 60 the movement of the pusher, when the cans are at rest. This operation is continued until all the cans in the way *j'* have been pushed out of the same and supplied with brine and have been replaced by empty cans, when the 65 switch-tracks W' and X' are moved over to coincide with the way *j* and the filled cans in

this way *j* also pushed out of the same and filled with brine and replaced by empty cans in the same manner as heretofore described with reference to the way *j'*. It will now 70 be observed that all the cans under the gate-plate and slide are empty and that by a repetition of the several operations described, the machine is caused to fill the cans and brine them successively until the supply is 75 exhausted. The filled cans, as soon as they reach the end of the fixed track X are removed by an attendant who stakes them into suitable grates for further processing and 80 capping.

I now call attention to the fact that the pump D'' has a capacity somewhat in excess of a single charge for the can with each stroke of its piston, which surplus will pass to a waste-pipe Z, Fig. 1, and back to the brine- 85 tank from which the pump takes its suction, and that by making the crank-pin *d''* of the pump adjustable to vary its stroke, I am enabled to gage the charge of the brine accordingly and to allow for any variation in the 90 size of the cans as made by different manufacturers. It will be further observed that the rapping mechanism which strikes the tube-plate H and its accessories rapid blows to produce the jar necessary to discharge the 95 peas from the tubes is here shown to consist of the cross-head S operated by the eccentrics R R' and the connections *r r'*. This mechanism, however, may be varied and other equivalent devices substituted without changing the 100 nature of my said invention. So may cylindrical tubes J be substituted for the taper tubes shown, as long as these tubes are made of a sufficient length and diameter to contain a full charge of peas for a single fruit can. 105 It will be further observed that by the introduction of the gate-plate and the adjusting device for varying the distance between the tube-plate H and gate-plate K, I am enabled to alter the cubical contents of the tubes J 110 and thereby adapt them for use in connection with different sizes of cans, it being a fact that manufacturers of fruit cans have a slightly different standard of size for cans of the same 115 denomination.

The most essential requirement of a machine for filling peas into fruit cans is that the berries shall not be lacerated, broken or squashed in the least but retain their shape perfectly. This result cannot be obtained by 120 mechanism having a plunger or forcer to discharge the peas from a hopper or cylinder, a fact which has thus far prevented the employment of mechanical fillers for peas.

By the adoption of a rapping device, substantially as described, I have successfully accomplished the task of producing a mechanical filler for peas, because by sufficiently jarring the measuring and filling tubes, said 125 peas will readily drop out of the same into 130 the cans placed below, and without the least injury to the berries.

In the foregoing description I have mentioned the tube-plate as being provided with the upwardly-projecting studs h'' upon which the cross-head S strikes. I have arranged these studs in the manner described so that the cross-head S shall not directly touch the tube plate for the reason that if the surface of the cross-head were to come in contact with the plate, peas which may be upon said plate would be mashed, a result which I desire to avoid. As an equivalent for these studs I may mention projections on the lower side of the cross-head, as shown in dotted lines in Fig. 5, though other means may be devices to accomplish the desired result, while at the same time these studs may be dispensed with if desired, and in claiming the device I desire it to be understood that I shall not confine myself to the use of said studs. It may here also be remarked that the filling opening in the cans, usually termed "hole" is supposed to be of nearly the same diameter as the lower end of the tubes J . By making these tubes tapering I attain the advantage of a larger filling mouth for the tubes, though cylindrical tubes as stated may be substituted without changing the nature of my said invention.

Having thus fully described my invention, I claim as new and desire to secure to me by Letters Patent of the United States—

1. In a machine for filling cans with peas, the combination, with a fixed receiver, of a series of gaging tubes a vertically-movable plate, to which said tubes are attached, means for normally maintaining said plate off its support, a gate at the lower end of the said gaging tubes, and mechanism substantially as described, for jarring the plate to which the tubes are attached, as and for the object stated.
2. In a machine for filling cans with peas, the combination, with a fixed receiver, of a series of gaging tubes a vertically movable plate, to which said tubes are attached, means for normally maintaining said plate off its support, a gate at the lower end of said gaging tubes, mechanism substantially as described for jarring said plate and tubes, and means for moving the cans intermittently, as and for the object specified.

3. In a machine for filling cans with peas, the combination, with a fixed receiver, of a series of gaging tubes a vertically moving plate, to which said tubes are attached, means for normally maintaining said plate off its support, a gate at the lower end of said gaging tubes, mechanism substantially as described for jarring said plate and tubes, means for moving the cans intermittently, and a brining mechanism for brining the cans while at rest, as and for the purpose stated.

4. In a machine for filling cans with peas, the combination, with a receiver for the peas, of a series of gaging tubes secured to a plate as described, and a jarring mechanism consisting essentially of a cross-head striking

said plate, eccentrics and connecting rods, a driving shaft, and mechanism for revolving said shaft, as stated.

5. In a machine for filling cans with peas, the combination, with a receiver for the peas, of the gaging tubes having a gate at their lower end, a pusher operated by suitable mechanism, a hopper, a fixed track and a switch-track, for guiding the cans into the ways underneath the tubes, as and for the object set forth.

6. In a machine for filling cans with peas, the combination, with a receiver for said peas and measuring tubes having a gate at their lower end, of mechanism for placing the cans into position underneath the said tubes, consisting of a reciprocating pusher, a hopper, fixed tracks at the ends of the machine, switch-tracks for leading the cans into ways underneath the tubes, and means, substantially as described for changing the switch-tracks simultaneously, as and for the purpose stated.

7. In a machine for filling cans with peas, the combination, with the receiver having the recessed bottom G' , of the jarring mechanism, the vibrating measuring device consisting of tubes J the tube plate H , to which said tubes are attached, the spiral springs h' underneath the said tube plate, the gate plate K , the slide K' underneath the gate plate, and the adjusting screws for the gate plate, as and for the object set forth.

8. In a machine for filling cans with peas, the combination, with a suitable frame, of a stationary receiver, at the upper portion of said frame and having a recessed bottom as described, the tube plate in said recess the springs underneath and means for limiting its upward movement of said plate, the gaging tubes secured to said tube plate, the steady plate secured to said tube plate by screw rods having adjusting nuts as described, the gate plate having the circular apertures for the reception of the lower ends of the said tubes, a gate having apertures corresponding with those of the gate plate and sliding within grooves in said gate plate, and the adjusting screws on the gate plate, as and for the use and purpose specified.

9. In a machine for filling cans with peas, the combination, with the receiver G , of a rapping mechanism for the filling tubes, consisting, in combination with the tube-plate having studs, as described, of the cross-head S reciprocating in guides $S' S''$, above the tube plate, the connecting rods $r r'$, eccentrics $R R'$, shaft P having suitable bearings, the bevel wheel p upon said shaft P , the bevel wheel p' , pulley Q and clutch q upon said shaft P' , and means for rotating the pulley Q , as and for the purpose set forth.

10. In a machine for filling cans with peas, the combination with the frame, of the track-board F secured upon cross-rail D and cross-board C , the fixed tracks $W X$ on the ends of

the track-board, the switch-tracks W' X'
hinged to said fixed tracks, the tracks f f' f''
upon said track-board, the connecting rods
x x', and the levers Y Y' fulcrumed at y y'
5 and having their meeting ends connected, as
described, for moving the switch-tracks si-
multaneously, as and for the purpose indi-
cated.

In testimony that I claim the foregoing as
my invention I have hereunto set my hand in ^{to}
the presence of two subscribing witnesses.

A. J. TANNER.
